UNITED STATES PATENT OFFICE.

HARRY B. WIER, OF PLAINFIELD, NEW JERSEY, ASSIGNOR TO WESTERN ELECTRIC COMPANY, OF NEW YORK, N. Y., A CORPORATION OF ILLINOIS.

TELEPHONE-RECEIVER.

1,148,941.

Specification of Letters Patent.

Patented Aug. 3, 1915.

Application filed October 28, 1913. Serial No. 797,759.

To all whom it may concern:

Be it known that I, HARRY B. WIER, a subject of the King of England, residing at Plainfield, in the county of Union and State 5 of New Jersey, have invented a certain new and useful Improvement in Telephone- Receivers, of which the following is a full, clear, concise, and exact description.

This invention relates to telephone receivers, and more particularly to receivers for use with wireless telephone and telegraph circuits, and its objects are to provide a structure which will withstand the hard and rough usage obtaining in this class 10 of service, to provide means for readily adjusting the air gap between the magnet and diaphragm and for maintaining said adjustment and, in general, to simplify and improve their mechanical construction.

20 In accordance with the features of the invention, there is provided a metal casing having adjustably mounted therein, a member carrying the pole-piece and magnet system of a receiver, the position of which, 25 with respect to the diaphragm carried by said metal casing, may be readily adjusted and locked while the receiver is in position on the operator's head.

This invention will be more fully understood by reference to the accompanying drawings, illustrating one embodiment of this invention, and wherein—

30 Figure 1 is a view in perspective of a receiver embodying this invention; Fig. 2 is a view in section on line 2—2 of Fig. 3, and Fig. 3 is a view in section on line 3—3 of Fig. 2.

As shown in the drawings, the receiver embodying this invention comprises a non- 40 magnetic shell or casing 5, externally threaded on one end as at 6, and internally threaded on the other end as at 7. A diaphragm 8 of magnetic material fits over one end of the shell 5 and is held in place 45 by a threaded cap 9 of insulating material, engaging the external threaded portion 6 of the shell 5. A plate 10 of non-magnetic material, having the periphery thereof threaded to engage the internally threaded portion 7 of the shell 5, is mounted therein. Mounted upon one side of the plate 10 and extending inside of the shell 5, is a permanent magnet 11 which is secured to the 50 said plate by means of screws 12, 12. Se-

cured to the permanent magnet are two pole- 55 pieces 13, 13, of magnetic material (only one is shown). Spools 14, 14, each containing a winding 15, are mounted upon the pole- pieces 13, 13, and are held in place thereon by locking plates 16, 16, of non-magnetic 60 material. Terminals 20, having extensions 21 extending within the shell 5, are mounted upon the outside of the plate 10, one being insulated therefrom by a washer 22, and the other being in direct electrical contact with 65 said plate. Each of the terminals 20 are provided with a screw 23 by means of which the conductors of a connecting cord 39 may be connected thereto.

To provide means for varying the distance between the diaphragm 8 and the ends of the pole-pieces 13, a block 25, having a threaded opening therein, is mounted upon the outside of the plate 5 near the margin thereof. The block 25 is engaged by a 75 thumb-screw 26. An outer casing 27 of brass or other non-magnetic material incloses the shell 5 and is held in place by a bayonet joint comprising pins 28 in the side of the shell 5, engaging angular slots 29 in the side 80 of said casing.

The outer casing 27 is provided with a slot 30 through which the thumb-screw 26 passes to engage the block 25. The thumb-screw 26 is provided with a shoulder 31 85 which, when said screw is tightened, engages the side of the outer casing 27 adjacent the slot 30 and maintains a definite distance between the ends of the pole-pieces and the diaphragm 8. To adjust the distance between the pole-pieces and the diaphragm, the thumb-screw is loosened; lateral bodily movement then of the screw in either direction will rotate the block 10 and, by reason of the threads thereon which engage the threads in the member 5, will cause a corresponding movement of the pole-pieces either toward or away from the diaphragm. When the desired distance is obtained, the thumb-screw is tightened against 95 the outer casing 27, thereby maintaining said desired distance.

The receiver may be suspended in a headband 35, terminating in an arc 36. Each end of the arc 36 has a pin 37 secured thereto, which engages registering holes 38 in the shell 5 and the outer casing 27, thereby supporting the receiver and preventing move-

ment of the outer casing 27 with respect to the shell 5.

The outer casing 27 may be provided with an opening 40 through which the cord conductors may be brought in to the terminals 20, and there may be mounted in the plate 10 a screw eye 41, to which may be secured the tie cord of the cord 39 to relieve the conductors of any strain.

10 It will be seen that I have provided a receiver which will withstand rough and hard usage, and in which the proper adjustment of the pole-pieces with respect to the diaphragm, may be readily obtained while an 15 operator has said receiver in operative position on his head, thereby enabling the operator to secure the proper adjustment more promptly than has heretofore been possible. Furthermore, it will be seen that the receiver 20 consists of few and simple parts easy to assemble.

I claim:

1. A telephone receiver comprising a cylindrical shell, a diaphragm mounted on one 25 end thereof, a rotatable plate having screw-threaded engagement with the other end of said shell, a magnet mounted upon said plate in operative relation to said diaphragm, a slotted member secured to said shell, a lug secured to said plate, and a screw engaging said lug whereby said magnet may be moved 30 toward and from said diaphragm and en-

gaging said slotted member to maintain the adjusted position of said magnet.

2. A telephone receiver comprising a cylindrical shell, a diaphragm mounted on one end thereof, a rotatable plate having screw-threaded engagement with the other end of said shell, a magnet mounted upon said plate in operative relation to said diaphragm, a lug secured to said plate, and a screw engaging said lug whereby said magnet may be moved toward and from said diaphragm and engaging said shell to maintain the adjusted position of said magnet. 40 45

3. In a telephone receiver, in combination with a casing, a diaphragm, a magnet, a plate having said magnet mounted thereon adjustably engaging said casing, a second casing having a slot in the side thereof enclosing said first mentioned casing, a block mounted on said plate, and a screw engaging said block whereby said magnet may be moved toward and from said diaphragm, and engaging said second casing to maintain 50 55 the adjusted position of said magnet.

In witness whereof, I hereunto subscribe my name this 25th day of October A. D., 1913.

HARRY B. WIER.
